(57) CLAIM

The ornamental design for an arm sleeve cover, as shown and described.

DESCRIPTION

FIG. 1 is a front perspective view of an arm sleeve cover, with an arm and a wrist shown in broken lines for context;

FIG. 2 is an isometric view of the arm sleeve cover showing my new design;

FIG. 3 is a right side view thereof;

FIG. 4 is a left side view thereof;

FIG. 5 is a front elevational view thereof; and,

FIG. 6 is a rear elevational view thereof.

The arm and the wrist shown in broken lines in FIG. 1 denote the nature and environmental use of the design and is shown for illustrative purposes only. The broken lines form no part of the claimed design.
